UNITED STATES PATENT OFFICE.

HARRY E. OYER, OF BUFFALO, NEW YORK.

DESIGN FOR A BADGE.

SPECIFICATION forming part of Design No. 30,932, dated June 6, 1899.

Application filed April 15, 1899. Serial No. 713,207. Term of patent 3½ years.

To all whom it may concern:

Be it known that I, HARRY E. OYER, a citizen of the United States, residing at Buffalo, in the county of Erie and State of New York, have invented and produced a new and original Design for Badges, of which the following is a specification, reference being had to the accompanying drawings, showing a part thereof.

10 In the drawings, Figure 1 is a face view of my original design. Fig. 2 is a sectional view taken through the line X X.

As shown in the drawings, the general outline of my design is triangular in shape, or-
15 namented with an illustration, in which are portrayed the Western Hemisphere, the mythical god Pan, an American Indian, an Indian wigwam, and the head of a buffalo.

These several features of the design are ar-
20 ranged as shown in the drawings, the Western Hemisphere occupying the center of the de-
sign, to the left of which is shown the mythical god Pan in a sitting posture and playing a musical instrument. To the right of the
25 hemisphere is shown the American Indian, also in a sitting posture and in the act of smoking the pipe of peace. Projecting above

the view of the hemisphere and forming a general background to the features just de-
scribed is the wigwam, and over the center of 30 the wigwam is shown the head of the buffalo. Running parallel with each other and ar-
ranged one above and one below the view of the hemisphere are the horizontal panels 1 and 2, which afford space for any suitable 35 words or dates.

The design consists in a triangular plate, on which is stamped, printed, or engraved an illustration, showing a view of the Western Hemisphere, the mythical god Pan, an Ameri- 40 can Indian, a wigwam, and the head of a buf-
falo.

Having thus described my invention, what I claim, and desire to secure by Letters Pat-
ent, is— 45

The design for a badge as herein shown and described.

In testimony whereof I have signed my name to this specification in the presence of two subscribing witnesses.

HARRY E. OYER.
